DATA REPRODUCING MACHINE

Arthur H. Dickinson, Scarsdale, and Robert I. Roth, Valley Stream, N. Y., assignors to International Business Machines Corp., New York, N. Y., a corporation of New York

Application June 16, 1939, Serial No. 279,507

9 Claims. (Cl. 164—115)

This invention relates to a data reproducing machine and more particularly to a machine capable of reproducing coded data representations from one type of data carrying medium to another and different type of data carrying medium. The present application is a modification of applicants' copending application Serial No. 279,503 filed June 16, 1939.

The data carrying mediums may be of the types or forms suitably adapted for the automatic control of well known types of machines, such as statistical machines, typewriting machines, or the like. For example, in mechanized accounting systems, employing various types of known statistical machines, record cards, having data representations disposed thereon, are used for controlling the operations of the machines used in such systems; when utilizing the well known Hollerith type of statistical card, the data representations usually are in the forms of perforations, which are formed at different columnar index point positions. The codes employed may be of different types, such as the combinational perforation code system, or single perforation code system. It has been suggested to employ different types of control records other than the perforated record cards, for controlling the machines referred to, for example, one type suggested, being a record medium having a layer of light sensitive emulsion disposed thereon which, when exposed to suitable recording mechanisms and properly conditioned, is adapted to bear the data representations in the form of imperforate control spots disposed in various code positions thereon. These control spots, or index points, may then serve as light modifying or modulating areas for controlling the statistical or other operations of the machines.

It has been found that, when it is desired to employ such machines controlled by different types of control records, provision must be made, whereby the data representations carried by one type of records can be reproduced on the other type of records, or vice versa. To simplify the description of the present invention, the illustration and disclosure thereof, will be limited to suitable mechanism which may be conditioned, whereby the data representations, in the form of coded perforations on a record control card, can be reproduced on a photographic control record in the form of differentially positioned control spots, or vice versa. These features are claimed broadly in the said copending application.

In addition thereto, the present invention comprehends the use of a novel record card sensing means, whereby the data designations on the card are sensed by light rays, which rays are then utilized directly to form the photographic spot recording on the film record. For this purpose, a transparent rotary card drum is provided, hav-

ing a suitable light source disposed within the drum and arranged, so that, as the record cards are fed singly around the drum, the rays of light are permitted to impinge upon the film record, at predetermined positions thereon, depending upon the time of sensing the perforations disposed on the record card.

Light conducting elements are provided at a predetermined position opposite the card drum, which position will be referred to as the record card sensing position, which conduct the light rays directly to the photographic film record. The position of the light conducting elements opposite the film record will be, hereinafter, referred to as the film record sensing position. Obviously, during the film record recording operations the record cards are fed around the card sensing drum, however, additional means are provided, whereby the record cards are fed so as to shunt the said drum during record card recording operations. This method of operation is employed, since it is preferred to use the same light source, during film sensing operations, as is used for the film recording operations. It will be understood, under these conditions, that it is necessary to shunt the feeding of the record cards past the card drum, so that these cards do not interrupt the light rays emanating from the light source.

Therefore, one of the objects of the present invention is the provision of novel record card feeding means, whereby for one type of reproducing operation the cards are directed along one predetermined path, whereas for a different type of reproducing operation the cards are directed along another predetermined path.

Another object of the present invention resides in the provision of a novel record card sensing means, whereby the perforated cards are sensed by light rays which are used directly for reproducing the control spots on the film record.

Another object of the present invention is the provision of means, whereby light rays are initiated at predetermined timed intervals by the card itself for effecting reproducing of the data sensed upon a film record directly by means of the initiated light rays.

Another object is the provision of a circular transparent drum containing a light source, the light rays of which are normally blocked off by the imperforate areas of the card during the card sensing operations.

Other objects of the invention will be pointed out in the following description and claims and illustrated in the accompanying drawings, which disclose, by way of example, the principle of the invention and the best mode, which has been contemplated, of applying that principle.

In the drawings:

GENERAL DESCRIPTION

35 Briefly and broadly, the instant application discloses, by way of illustration, record card sensing and recording means, photographic film sensing and recording means, and associated control elements, all of which when suitably conditioned render the device effective, (1) for sensing the data representations, in the form of perforations on the record card, and thereafter controlling the film recording means, at differential times, thereby reproducing the sensed data representations on the photographic film, in the form of 40 discrete control spots, in different index point positions, (2) for sensing the differentially positioned control spots on the photographic film to control the record card perforating, or recording means, at differential times, thus reproducing the data representations sensed on the record cards in the form of differentially displaced perforations, or the like.

45 Referring now to Fig. 1, the data reproducing mechanism, or device, is shown to comprise a record card magazine, or supply hopper M, from which the cards are fed singly by the card feeding means, comprising in part, the card picker 47, 48 and actuating arm 46 therefor, to the feed rollers 80 to 83, from where the cards are fed 50 through the card guide 115, and around the circumferential surface of the transparent card drum 120, to the feed rollers 122 and 123, and card stacking magazine, or hopper N, during film recording operation; whereas, during record card 55 perforating operations the cards are fed from the said feed rollers 80 to 83, so as to shunt the card drum, by means of and through the card guide assembly 116 (which is tilted so that the card guide 241 occupies the position in the dotted 60 outline), to the feed rollers 122 and 123, and thence to the hopper N. Interposed between the pairs of feed rollers 80, 81 and 82, 83 is shown one suitable type of card recording means, for example, the punch plungers 65 and control mag- 65 nets 66 therefor.

The photographic film record 180 is fed, by means of the driving sprockets 213, and associated mechanism from a supply reel 200, past a suitable sensing and recording station to the suitably disposed take-up reel 201. The said 5 sensing station comprises the light source 258, quartz element as shown in Fig. 11, quartz rods 267, and related photocells 183; and the film recording station comprises the said light source 258 and quartz rods 264.

10 By referring to Figs. 7 and 8, facsimiles of portions of the perforated record cards and recorded photographic film are shown. In Fig. 7 the reference character 53 represents the differentially disposed perforations on the record card 52, 15 whereas in Fig. 8, the reference character 181 represents the differentially disposed control spots, or light modifying areas on the control film record 180.

Record card feeding means

20 Referring now to Figs. 1 to 4, it will be shown, how the card feed magnets 20 control the operation of the record card feeding means. A motor 21 (Fig. 14), suitably mounted in the machine, 25 is effective to rotate the shaft 24, by means of the interconnecting belt 22, pulley 23, pawl 25 secured to said pulley, and ratchet 26 which is secured to shaft 24, and engaged by the pawl 25. In this manner, the shaft 24 is rotated continuously as long as the motor is operated. Gear 27, attached to the shaft 24, is effective to drive gears 28 and 29, by means of the interconnecting gears 30 and 31, both of which are affixed securely to shaft 32. Gear 29 is secured to shaft 33, thus it is seen, that shafts 32 and 33 are arranged to be rotated continuously, similarly as shaft 24, as long as the motor is operated. A single tooth ratchet 35 is secured to gear 28, both gear and ratchet being rotatably mounted 35 on the supporting shaft 34, and to which shaft an arm 36 is attached. A spring actuated dog 37 is pivotally mounted on the arm 36, and arranged to be held out of engagement with the ratchet 35 by the armature 38, which armature 45 is associated with and controlled by the magnets 20. From the description thus far, it is understood, that upon energization of the magnet 20, the associated armature 38 is displaced sufficiently out of the path of dog 37 and arm 36, to release these elements, and permit the dog 37 to engage the single tooth of ratchet 35, thus effecting rotation of the shaft 34, by means of the ratchet and associated gearing.

50 Complementary cams 42 and 43 (see Fig. 5) 55 are mounted on shaft 34, and are arranged to displace the two armed lever 44 on shaft 45, thereby rocking shaft 45 and the sector arms 46 (Fig. 1) attached thereto. The said sector arms are provided with gear teeth which mesh with 60 racks on the card picker slides 47. A knife edge 48, attached to the slides, is adapted to engage the bottom card in the supply magazine, or hopper M, and displace the card to the right (Fig. 1), when the picker slide is reciprocated by the cams 65 42 and 43 on shaft 34. The ratio of the described gearing is such that gear 28 rotates one revolution for each card cycle. Associated with the card hopper M are the contacts 54 (Fig. 1a) 70 controlled by the lever 55, which contacts are adapted to remain closed, as long as cards are provided in the supply hopper, and upon exhaustion thereof, the said lever is permitted to swing in a clockwise direction to open the said contacts. 75

Upon deenergization of the magnet 28, the spring-urged armature 33 is positioned in the path of dog 37 and arm 36, so that disengagement of dog 37 and ratchet 38 is effected. A locking lever 49 is provided to maintain arm 36 in a predetermined position, thus locking the shaft 34 in the normal D or home position (see Fig. 13).

It should be mentioned, that shaft 33 carries cam elements 51 to control the associated cam controlled contacts C1 to C4; also upon shaft 33 (see Fig. 4) a suitable cam 56 (see Fig. 14) is mounted which is adapted to operate the associated contacts 51 at different times during the machine cycle (see Fig. 13).

It has now been shown, how the record cards 52 are fed singly from the supply hopper M, by means of the card picker mechanism, whenever the control magnet 28 is energized. For further detailed description of the card feeding mechanism reference may be made to U. S. Reissue Patent No. 21,133 dated June 27, 1939, wherein elements similar to those just described are shown in detail. The individual record cards are now displaced and fed to the first set of feed rolls 80 and 81, which in turn feed the cards past the card recording or perforating station. It will be shown, that the individual cards are positioned intermittently, by the feed rollers, not only past the card recording station, but also past the card sensing station. This mechanism will now be described in conjunction with the card recording or perforating means.

Record card recording means

Referring now to Fig. 1, the card recording station is shown to comprise recording means, illustrated in the form of record card perforating plungers 65, the operation of which are selectively controlled by the magnets 66. The said magnets, upon energization, select the associated plungers so that, during the operation of the operating bar 67, the bar depresses or operates all the selected plungers and thereby effects perforation of the record card. This operation is explained in detail, in the patent referred to hereinabove, and therefore the following brief description thereof is deemed sufficient. It is well known, that an individual plunger 65 and controlling magnet 66 are provided for each columnar area of the card, and that all the selected plungers are operated or depressed for all columnar areas simultaneously. It will be explained shortly, how the different index point positions of the cards are fed, intermittently, to the punching station, and that the perforating thereof is effected while the cards are stationary thereat.

The said plungers are shown provided with individual spring-urged pivoted interposer pawls 68, which are connected to the armatures 69 of the magnets, by call wires 70, so that, upon energization of a magnet, the connecting call wire is effective to swing the pawl 68 to the right, as viewed in Fig. 1, positioning the said pawl in the path of the operating bar 67. Upon depression of the said bar, which is adapted to cooperate with the notch 68a in the pawl, the related pawl is caused to be depressed to perforate the record card accordingly, and is then quickly withdrawn therefrom to permit feeding of the card to the next index point position.

The operating bar 67 is supported by a control ball 71 which is suitably pivoted on studs 72. The control ball is attached to arm 73, by means of an adjustable turnbuckle connection 74, said

arm 73 being secured to shaft 76 which is also provided with an arm 78. An eccentric 77 is suitably disposed and formed on the shaft 24, which eccentric is encircled by an arm 78, the upper end of which is pivotally connected to the 5 said arm 76.

It is now seen that, since the eccentric 77 is positioned on the constantly rotating shaft 24, shaft 76 and arm 78 are rocked to depress, at periodic intervals, the ball 71 and bar 67. As the 10 said ball and bar are reciprocated, any of the pawls may be positioned by the call wires so as to effect engagement of the pawls and bar. Then, the connected pawls and plungers are depressed to perforate the card, and thereafter withdrawn 15 immediately therefrom to permit the feeding of the card. Referring to Fig. 7, a facsimile of a portion of a perforated record card 52 is shown, the index point position for several columnar areas are shown to be provided with perforations 20 53, at different positions in the columnar areas, to represent different data representations.

The feeding of the cards to, and from, the punching station is effected by the feed rollers 80, 81, 82 and 83. The cards are fed intermittently, by rollers 80 and 81, between a stripper plate 84 and die plate 85, through which plates the plungers are adapted to be positioned.

The mechanism for operating the said feed rollers is as follows—referring now to Figs. 5 and 30 6, it is seen, that the continuously rotated gear 27 (also see Fig. 2) is provided with a Geneva roller 86 and segment 87, which cooperate with a Geneva disc 88 fixed on shaft 89. The Geneva disc is provided with seven radial slots, so that 35 one revolution of gear 27 will rotate the shaft 89 one-seventh of a revolution, which partial revolution corresponds to a movement of one cycle point of the record card. Shaft 89 rotates continuously with an intermittent motion, as long as the 40 motor 21 is operated. Rotatably mounted on the shaft 89 is a gear 90, which has affixed thereto a single tooth ratchet 91, and secured to the shaft 89 is an arm 92, upon which a spring-urged dog 93 is pivoted. The spring-urged dog normally tends to engage the ratchet 91, however, disengagement of the dog and ratchet is effected by the lever 94 and attached roller 95, which roller as shown in Fig. 5 engages the tail of the dog to position it, so as to prevent engagement thereof 45 with the ratchet. When the said lever and roller are positioned to the right, as viewed in Fig. 5, and out of the path of the dog, the dog and ratchet are permitted to be engaged, thereby effecting rotation of gear 90 which is arranged to 50 drive gears 96 and 97, which gears are fixed to shafts 98 and 99, respectively. Suitably disposed on shafts 98 and 99 (see Figs. 1 and 2) are gears 100 and 101, arranged to engage gears 102 and 103, which are pinned to shafts 104 and 105, 60 respectively. Shafts 98 and 104 carry the first pair of feed rollers 80 and 81, respectively, whereas the second pair of rollers 82 and 83 are carried by shafts 99 and 105, respectively.

It is evident now, that whenever the lever 94 65 is displaced out of the path of dog 93, engagement of the dog and ratchet 91 is effected to drive the feed rollers 80 to 83, intermittently, by means of the described gearing. As mentioned hereinabove, the gear ratio is such, that for each 70 movement of shaft 89, the feed rollers are rotated to an extent sufficient to displace the card one cycle point, which displacement is equivalent to the distance between index point positions on the record card. The lever 94 is displaced, so as to 75

release the dog 93, by the complementary cams 106 and 107 positioned on shaft 34, which, are engaged by the rollers 108 and 109 carried by the horizontal portion of lever 94. It is remembered, that the rotation of shaft 34 is controlled by the magnet 20, and that, whenever this magnet is energized, shaft 34 is rotated continuously by the shaft 24 and associated gearing, described hereinabove. The cams 106 and 107 are designed, so that, if the magnet 20 is not energized and the shaft 34 is not rotated, lever 94 is positioned in the path of the dog 93, thereby preventing the dog from engaging the driving ratchet 91. However, should the said magnet be energized, cams 106 and 107 are turned, lever 94 displaced, permitting engagement of the said dog and ratchet, and establishing a driving connection between the intermittently driven shaft 89 and gear 90 for effecting intermittent movement of the card feed rollers 80 to 83.

Adjacent to rollers 80 and 81 is suitably disposed a control lever 111, which lever is effective to close a pair of associated contacts 110 (Figs. 1a, 1b and 14) as long as cards are fed successively to, and from, the rollers 80 and 81, however, when cards are not fed successively thereto, the said contacts are opened.

Record card sensing and stacking means

Referring now to Fig. 1, the record cards are fed from the recording station to the card retaining hopper N, by the rollers 82 and 83, by one of two different routes. The routing of the cards is controlled by the positioning of the card guide assembly 116, which when positioned as shown in Fig. 1 so that the card guide plate 241 occupies the position shown by the solid outline, the cards are directed through the card guides 115 to be fed, by the card drum 120, past the card sensing station, and to the hopper N by means of rollers 122 and 123. When the card guide assembly 116 is positioned, so that the card guide plate 241 is positioned, as shown by the dotted outline, the cards are directed to the card hopper N, by shunting the card drum. The said drum and feed rollers are operated continuously, with an intermittent motion, and in a synchronous relationship with the feed rollers 80 to 83.

Referring now to Figs. 2, 5 and 6, it is remembered, that shaft 89 is rotated continuously with an intermittent motion. This shaft has secured thereto gear 124, which drives gears 125 and 126, both of which gears are mounted on a common hub 127 which is rotatably supported by shaft 99. By means of the gearing, comprising the gear 128 pinned to idler shaft 129, gears 130 and 131 pinned to shaft 132, the gear 126 is effective to rotate the gear 133, and associated shaft 134 upon which is mounted the card drum 120 (see Figs. 1 and 10).

Pinned to the opposite end of shaft 134 is a gear, not shown, but similar in size to gear 133, and which is arranged to drive gear 135 and its related shaft 136, upon which the feed roller 121 (Fig. 1) is mounted; thus, it is seen that the card drum and associated feed roller are rotated continuously, with an intermittent motion, as long as the motor is energized, and in synchronism with the operation of the feed rollers 80 to 83, since the controlling drive shaft 89 is the common drive for both the controlling gearings. The gear ratios between gears 124 and 133 are such that one-seventh of a revolution of gear 124 will

displace the drum upon which the cards are held, one cycle point.

Gear 130 also drives gear 137 and related shaft 138, upon which shaft is mounted gear 139 which drives the gearing, comprising gears 140 and 141 pinned to shaft 142, gears 143 and 144, the latter gear being pinned to shaft 145. Upon the shaft 142, a feed roller 123 (Fig. 1) is mounted, and by means of a gear similar to gear 141, mounted on the shaft 142, the gear 146 and related shaft 147 are driven; feed roller 122 is mounted on shaft 147 and rotated thereby.

From the feed rollers 122 and 123 (Fig. 1) the cards are stacked in the hopper N, whereat provision is made to insure proper insertion of the cards in the stack, by providing a rubber stacker roll 148 mounted on shaft 145, which when rotated, by means of the said shaft, urges the cards to the right as viewed in Fig. 1.

Referring now to Figs. 9 and 12, the card guide assembly comprises plates 230 which are loosely mounted on shaft 138. Secured to the top of the plates are card guides 115, which guide the cards, when reproducing from cards to film, to the card drum 120. One of the plates 230 is provided with a downwardly extending member 231, which carries suitably positioning means, such as the rod 232 and knob 233. The knob 233 is provided with a pointer 234 for indicating the positions of the card guide assembly. The member 231 is provided with two notches 235 which cooperate with the detent 236 pivoted on a stud 237 suitably fastened to a side frame of the machine, said detent being urged into the notches by spring 238. Thus, by manually positioning the knob, the card guide assembly can be moved to either one of two positions, one position when reproducing from cards to film, and the other position when reproducing from film to cards.

Extending between the plates 230 and secured to them are the rods 239 to which the card guide plate 242 is fastened. Card guide plate 241 is suitably secured by bracket 240 to the plates 230. The card guide 241 (see Fig. 12) is shown to be formed along its upper edge by a series of spaced extensions 243, so that, when the card guide assembly is positioned for film to card operations, the extensions are positioned within the spaces between the feed rolls, thus insuring that the cards will be directed through the said assembly.

The plates 230 support the spaced shafts 244 and 245 and upon the first mentioned shaft feed rolls 246 are secured. Cooperating with the said feed roll are the spring urged pressure rollers 247 which are pivotally mounted on the links 248. A similar pressure roller 249 is provided to cooperate with the feed roll 250 which is secured to shaft 138. Also secured to shaft 138 is the gear 251 which is effective to drive the gear 252 secured to shaft 244, by means of the idler gear 253 revolvably mounted on the shaft 245. Thus, it is seen, that the feed rolls 246 and 250 are continuously rotated, with an intermittent motion, by means of the gear 251, to direct the cards directly to feed rolls 122 and 123 when the card guide assembly is positioned for film to card operations.

Now, when the card guide assembly is positioned for card to film operations, the card guides 115 are positioned, as shown in Fig. 1, to guide the cards to the feed roll 121, secured to shaft 136, cooperating with the card drum 120, thereby feeding the cards around the said drum, and thence to the feed rolls 122 and 123 to the hopper N.

Referring now to Fig. 10, the card drum 120 is

shown to comprise a shell 255 of suitably transparent material, which is secured to end plates 256 constructed of insulating material, which are shown secured to the shaft 134. On the inside surface of each end plate, suitable conducting spring clips 257 are provided for holding the tubular light source 258. The said spring clips are connected by the wires 259 to slip rings 260, mounted in the end plates, which are adapted to cooperate with suitable brushes, not shown. The card drum is provided with a plurality of pivoted gripping fingers 149. These fingers are urged into card gripping position by the springs 150. Fixed face cams 151 are provided to be suitably disposed, so as to cooperate with the fingers to effect their opening and closing at the proper time. The timing of the fingers is such, that the record card is gripped after it passes the feed roller 121, and held securely to the drum as it rotates to further advance the card, and finally releasing and discharging it to the feed rollers 122 and 123.

It should be mentioned, that between feed rolls 82 and 121 a suitable and well known type of card lever 118 (Fig. 1c) is provided for controlling the associated card lever contacts 119. Whenever a card is fed through the guide plates 115, the said card lever is operated by the cards to close the card lever contacts, and whenever no cards are present to engage the card lever, the card lever contacts are opened.

It will be explained presently, that as the cards are fed to, and around the card drum, the differentially positioned perforations in the cards will permit the light rays from the light source 258 to be impinged upon suitable light conducting rods for recording purposes. The sensing of the cards in the present application is effected by the light rays passing through the perforations in the card, which light rays are then employed directly for recording purposes.

Film sensing and recording means

With reference to Fig. 1, the film record 180 is shown to be fed through a gap formed by the two members 261 and 262. The said members are supported by the rails 263 which are fastened to suitable side frames in the machine. It is intended, that the members 261 and 262 are slidably arranged on the rails, so that each member can be withdrawn as desired and substituted by another like member. The member 261 is provided with a plurality of individual quartz rods 264 which are embedded therein, and disposed in the same horizontal plane. The quartz rods 264 (see Fig. 10) extend from the photographic film record 180 to the card drum 120, so that whenever rays of light, from the light source 258, are impinged thereon these light rays are conducted, by the individual rods to the film record 180, to effect recording thereon, at different positions, in various columnar areas thereon. The spacing of the quartz rods at the card drum end are such as to correspond to the spacing of the columnar areas on the record cards (see Fig. 7), and the spacing of the said rods at the film end are equivalent to the spacing of the columnar areas of the film record (see Fig. 8).

In the instant application, the film is fed intermittently to and from, the group of quartz rods 264, by means to be described later herein, so that the index point positions of the film are presented successively thereto. Referring to Fig. 8, a facsimile of a portion of the film record 180 is shown, wherein the index points are shown

differentially disposed in various index point positions in the columnar areas. Now assume, that an unrecorded photographic film record is presented intermittently to the said quartz rods, so that the feeding of the index point positions is in a timed relationship with the feeding of the index point positions on the cards, by means of the card drum, past the said quartz rods. A facsimile of a portion of a suitable perforated record card 52 is shown in Fig. 7, provided with differently positioned perforations 53 in various columnar areas.

It is understood, as the perforated cards are fed past the quartz rods 264, whenever perforations are presented thereto, rays of light are permitted to be conducted by the rods opposite the columns, in which the perforations occur, to the photographic film record to effect recording of spots thereon, in the columns opposite the quartz rods 264, the positions of said spots in the columnar areas corresponding to the positions of the perforations in the columnar areas thereof.

Now, whenever it is desired to sense the differentially disposed spots on a recorded film record, the member 261 with the individual quartz rods 264, is substituted by a member 265 (see Fig. 11) provided with a single quartz element 266 wide enough to transmit a narrow line of light across the width of the film record 180. It is understood, when film to card reproduction is effected, the cards are directed so as to shunt the card drum, so as not to interrupt the light rays emanating from the source 258. It is evident then, that the rays of light are now transmitted by the quartz element 266 in a horizontal line to the film record 180. In the member 262, a plurality of individual quartz rods 267 are provided, which are disposed in the same plane as the element 266, and arranged so that the spacing thereof at the film record end corresponds to the columnar spacing of the index point positions on the film record. The individual rods 267 are arranged to conduct the rays of light to related photocells 183, so that as the film record is fed intermittently past the quartz rods 267, and whenever control spots are presented thereto, the light rays are blocked or cut-off from the corresponding quartz rods 267, and in turn from the related photocells 183. In this manner, the photocells are conditioned for control purposes which will be described hereinbelow.

Film feeding means

Referring now to Figs. 1, 2 and 4, the means for feeding the photographic film from the supply reel 200 intermittently to, and from the sensing or recording station, and to the take-up reel 201 comprise the following gearing, which gearing is controlled by the shaft 142, which as described herebefore, is rotated continuously with an intermittent motion. A gear 202, pinned to shaft 142, is arranged to drive the gear 203 rotatably mounted on shaft 204; attached to gear 203 is the single tooth ratchet 205, which is arranged to cooperate with the dog 206, pivotally mounted on the arm 207, which arm is fixed to the shaft 204. The armature 208 of magnet 209 normally, when the magnet is deenergized, is adapted to be positioned in the path of the said arm and dog, thereby preventing engagement of the dog 206 and ratchet 205. However, upon energization of the said magnet, the armature is displaced sufficiently to release the dog, thereby permitting engagement of the said dog 75

and ratchet, thus effecting rotation of shaft 204 by means of gears 202 and 203.

Secured to shaft 204 is the gear 210 engaging gear 211, which is fastened to shaft 212, upon which shaft 212 is mounted the film drive sprocket 213. Also secured to shaft 212 is a pulley 214 which, by the connecting belt 215, is adapted to rotate the shaft 216 upon which the take-up reel 201 is mounted. Thus, it is seen, that the film 180 is fed to, and from, the sensing and recording station, intermittently, by means of the driving sprocket 213 and the described gearing. It should be mentioned, that contacts 218 are provided and adapted to be closed by the lever 219, whenever the film record 180 is present in the sensing unit, and are arranged to be opened whenever the film record supply is exhausted.

Operation of the machine

- 20 Referring now to Fig. 14, the operation of the machine will be described in conjunction with the circuit diagram shown therein. The description to be given first will relate to sensing the perforated cards, and reproducing the data representations sensed upon an unrecorded photographic film record, in the form of differentially positioned control spots. To effect this type of data reproduction, the machine must be conditioned accordingly, therefore, let it be assumed, 25 that the main switch MS is closed, that the control switches S1 to S4 are positioned in the CF positions as shown, that perforated record cards are provided in the supply hopper M, that the unrecorded photographic film record 180 is 30 properly inserted in the machine, and that the start key is depressed to close the associated contacts SK1 (and maintained depressed until automatic operations of the machine are established).
- 35 40 A circuit is then completed from conductor 300 to coils of relays R1 and R2, and the contacts SK1 to conductor 301, causing the said relays to be energized. Upon energization of relay R1, the contacts R1a are closed, to complete a circuit 45 from the power supply source to the drive motor 21, thereby effecting operation thereof to drive the associated gearing described hereinabove. Upon energization of relay R2, a holding circuit therefor is established by the associated 50 contacts R2a now closed, through the normally closed cam operated contacts C2. The contacts R2b are also closed, upon energization of relay R2, to effect energization of the card feed control magnet 20, by the circuit completed as follows: conductor 300, coils of magnet 20, contacts R5a now closed (since contacts 218 are closed), switch S2, contacts R2b and contacts C1 to conductor 301.

55 Upon energization of magnet 20, the shaft 34 is rotated to operate the card picker mechanism, thereby effecting the feeding of a card to the feed rollers 80 and 81. The gearing driving the feed rollers is also operated, when magnet 20 is energized and shaft 34 is operated. Thus, during the first machine cycle, the record card is fed, intermittently, up to the card perforating station, thereby causing the contacts 110 to be closed (operation of the contacts 110 causes relay R3 to be energized, which relay is used for control purposes only during card reproducing operations).

70 During the second machine cycle, the first card will be advanced to a position such that its leading edge is a short distance to the left of the card lever 118 (see Fig. 1), and a second card

will be fed up to the perforating station. During the third machine cycle, the first card is advanced to actuate the said card lever 118, and close the associated contacts 118, and to be positioned into the bite of the continuously running card drum 120 and its associated feed roll 121; also in this cycle, the third card is fed from the magazine M up to the perforating station. Near the end of the third cycle, contacts C3 are closed to permit energization of the relay R6, by means of the circuit completed from conductor 300 through coil of said relay, contacts 119 and C3 to conductor 301. Upon energization of relay R6, associated contacts R6d are closed, to complete a holding circuit for relays R1 and R2 which is as follows: from conductor 300, to coils of relays R1 and R2, contacts R2a, and R4a (relay R4 is energized by means of contacts 54), contacts R5b and R5b, switch S3, and normally closed contacts SK2 of the stop key to conductor 301.

75 The machine is now conditioned for continuous operation, and release of the start key can be effected, for it is seen, that relays R1 and R2 are now maintained energized during every machine cycle. Contacts 119 are closed as long as cards are fed to the card drum 120, at the end of each cycle, when the contacts C3 are closed to effect energization of relay R6, and by means of the holding circuit through contacts R6a and C4, the said relay is maintained energized during all of the following machine cycles. And, since contacts C3 and the contacts 119 are closed at the same time in the cycle, the holding circuit to the relays R1 and R2 is established 80 each cycle.

85 Upon energization of the relay R6, contacts R6c are also closed, to permit energization of the film feeding control magnet 209 as follows: conductor 300, coils of magnet 209, contacts R6c, 40 R2b and C1 to conductor 301. Energization of said magnet, permits the film feeding mechanism described hereinabove, to become effective to feed the film record 180, intermittently, to the sensing and recording station in timed relation 45 with the feeding of the record cards 52 past the associated sensing and recording stations. That is, for example, when the "9" index point positions on the card are presented for sensing thereof, the film record is fed to its recording station, 50 so that the "9" index point position of the individual frame, or portion, of the film record is presented to the film recording station.

55 Now, as the perforated cards are fed successively past the card sensing position, which is represented by the positions of the individual quartz rods 264, particularly the positions of the ends of the said rods opposite the card drum, it is evident, that the imperforate areas of the cards block off the rays of light emanating from 60 the source 258, within the drum from the individual quartz rods 264. It should be mentioned, that, by means of the cam controlled contacts 57, the light source is energized only when the index point positions on the cards are presented 65 to the quartz rods. However, upon presentation of the data perforations in cards to the sensing station, at differential times, the said perforations permit the light rays at such positions to be impinged upon the related quartz rods 264, and 70 be thus conducted thereby opposite the corresponding index point positions of the individual frames, or portions, of the film record to effect recording, at such positions, of individual control spots. Since the film record and record cards 75

are fed in synchronism past the respective sensing and recording stations, the data represented by the sensed perforations will be reproduced on the film record, in the form of differentially positioned control spots, the positions of which correspond to the position of the sensed perforations in the record cards.

In view of the description just set forth, and since the driving mechanism, feeding mechanism 10 and control circuits are operated, and conditioned in the same manner, for reproducing the data sensed upon recorded film records on the blank record cards, in the form of perforations, the following brief description is deemed sufficient. Assume now, that the control switches S1 to S4 are positioned in the FC position, and that the start key is depressed to close the contacts SK1, long enough to condition the machine for automatic operation. It will be understood for 20 this type of operation, whereby the recorded film record is sensed, and the sensed data is reproduced or perforated on the blank record cards accordingly, that upon feeding the film record the record cards must be presented at that time at 25 the punching station.

Now, upon energization of relays R1 and R2, the record card and film record feeding operations are effected. The magnets 20 and 209 are connected together, by means of switch S1, and 30 in turn connected to switch S2, and contacts R2b and C1. This circuit is completed and energized, upon closure of contacts R2b, which is effected by energization of relay R2. The first card is then fed up to the reproducing, or perforating station, to close the contacts 110. Assume, that the recorded film record was positioned in the machine, so that during the first machine cycle the first recorded frame is fed up to the film sensing station, so that film sensing and card recording operations are effected during the second machine cycle. Now, upon closure of contacts 110, relay R3 is energized, completing the holding circuit for relays R1 and R2, which is as follows, from conductor 300 to 40 coils of relays R1 and R2, contacts R2a, R4a, R5b, and R3a, switch S3 and contacts SK2 to conductor 301. Thus, at the end of the first cycle the machine is conditioned for continuous operation.

Now assume, that the quartz element 266 has 50 been substituted for the individual rods 264, and that the card guide assembly is tilted in the film to card position to divert the cards so as not to be fed around the card drum. In this manner, 55 the cards will not interrupt the rays of light emanating from the source 258. Normally, the rays of light are directed by the quartz element 266 to the film record, so that all the index point positions of the film record presented thereto are 60 illuminated, and whenever no control spots appear on the film record at the sensing positions, the rays of light are conducted from the sensing position to the related photocells 183. The associated amplifier units 302 are conditioned, so that 65 when light rays are impinging on the cells no current flows in the output circuit of the respective amplifier unit. However, whenever individual control spots, formed on the film record, are presented to the sensing station to block off the 70 light rays from the associated photocells, the associated amplifier units are then conditioned to be conductive, so that current flows in the relay circuits connected thereto. Now, upon energization of the relays R7 at the differential times 75 whenever the control spots are sensed, the punch

magnets 68 are adapted to be energized by the following circuits, which are established at such differential times; namely, from conductor 300 to magnets 68, conductors 303, contacts R1a to contacts 51 and conductor 301. Thus, it is seen, 5 that the record cards are perforated, at such index point positions, so as to correspond to the data sensed on the film record, and represented by the differentially positioned control spots.

While there has been shown and described and 10 pointed out the fundamental novel features of the invention as applied to a single modification it will be understood that various omissions and substitutions and changes in the form and details of the device illustrated and in its operation 15 may be made by those skilled in the art without departing from the spirit of the invention. It is the intention, therefore, to be limited only as indicated by the scope of the following claims. 20

What is claimed is:

1. A data reproducing machine controlled by individual record elements containing data to be reproduced, comprising card sensing and recording means and photographic record medium sensing and recording means, means for alternately feeding blank cards past the first mentioned recording means and recorded cards past the said card recording means, means for alternately feeding blank or recorded photographic record mediums past the second mentioned sensing and recording means, means for operating the said feeding means, in synchronism, so that the cards and said record mediums are presented to the respective sensing and recording means in a predetermined time relationship, means for selecting and rendering effective one type of sensing means for controlling the other type of recording means, thereby controlling the selected recording means, to reproduce the data upon the blank record elements presented thereto, in accordance with the data sensed upon the recorded record elements presented to the selected sensing means, and means for controlling the card feeding means for directing the blank cards past the related recording means, during card reproducing operations, 45 including means for directing the recorded cards past the related sensing means only during photographic record medium reproducing operations.

2. A data reproducing machine controlled by individual record elements containing data to be reproduced, comprising a first group of sensing and recording means adapted for sensing and reproducing data on record cards, a second group of sensing and recording means, means for alternately feeding blank cards past the card recording means and recorded cards past the card sensing means, means for alternately feeding a continuous record medium containing recorded or blank record elements past the second group of sensing and recording means, means for operating the feeding means, in synchronism, so that the said record elements are presented to the respective sensing and recording means in a predetermined time relationship, means for selecting and rendering effective the sensing means, of one group, for controlling the recording means, of the other group, thereby controlling the selected recording means to reproduce the data upon the blank record elements presented thereto, in accordance with the data sensed upon the recorded record elements presented to the selected sensing means, and means for controlling the card feeding means for directing the blank cards past the related recording means, during card reproducing operations, including means for directing the 75

recorded cards past the related sensing means only during operations when reproducing is effected on the said continuous record medium.

3. A data reproducing machine controlled by 5 individual record elements containing data to be reproduced, comprising a first and second group of record sensing and recording means, means for alternately feeding blank or recorded record elements past the sensing and recording means of 10 the first group, means for alternately feeding blank or recorded record elements past the sensing and recording means of the second group, means for operating the said feeding means, in 15 synchronism, so that the record elements are presented to the respective sensing and recording means in a predetermined time relationship, means for selecting and rendering effective the sensing means, of one of said groups, for controlling the recording means, of the other said 20 group, thereby controlling the selected recording means to reproduce the data upon the blank record element presented thereto, in accordance with the data sensed upon the recorded record element presented to the selected sensing means, and 25 means to direct the feeding of the one group of record elements along a certain path, when the said selected sensing and recording means are effective to reproduce data, including means to direct the feeding of the last mentioned record 30 elements along a different path when the other said sensing and recording means are effective to reproduce data.

4. A data reproducing machine controlled selectively by record card and photographic record 35 elements containing data to be reproduced upon photographic record elements and record cards respectively, comprising means for sensing the record cards, means under control of the sensing means for controlling the reproduction of the 40 data upon photographic record elements, additional means for sensing the photographic record elements, means under control of the last mentioned sensing means for controlling the reproducing of the data upon the record cards, and a 45 common light source included in both of said sensing means for effecting sensing of the said record elements.

5. A data reproducing machine controlled by 50 individual record cards containing data, in the form of perforations, to be reproduced, comprising a sensing station including a source of light rays, means for presenting the record cards to said sensing station whereat the light rays are adapted to pass through the perforations in the 55 cards, a photographic record medium, and means for directing the light rays, permitted to pass through the card, upon the said photographic medium, whereby the data sensed upon the record cards are reproduced upon the photographic medium.

6. A data reproducing machine controlled by 60 individual record cards containing perforations representing data to be reproduced, comprising a card sensing station, means for presenting successively the perforated cards to the said sensing station, a recording station, means for presenting individual photographic record areas to said recording station, means at the sensing station for analyzing the record cards, comprising a light source for detecting the perforations in the record 65 cards by the light rays passing through the per-

forations thereof, and means for directing the light rays, passing through the cards, to the recording station for reproducing the data upon the photographic record areas by the light rays impinging upon the said photographic areas. 5

7. A data reproducing machine comprising a sensing station, means for presenting perforated records to the said sensing station, the perforations in the records representing different data by the disposition thereof in the records, a recording 10 station, means for presenting individual photographic areas to said recording station, means at the sensing station for detecting the perforations in the cards, comprising a source of light rays, which rays are adapted to pass through the 15 differently positioned perforations therein, and means for directing the different rays, passing through the cards, to the recording station to impinge upon the photographic area presented thereto, at different positions in said area, corresponding to the positions of the perforations on the cards, thereby recording the sensed data upon the said photographic areas. 20

8. A data reproducing machine comprising a sensing station, means for feeding continuously 25 individual records successively past the sensing station, said records provided with data designations, comprising differentially positioned perforations, a recording station, means for feeding continuously photographic record mediums 30 past the recording station, means for operating the said feeding means, in synchronism, so that the record elements are presented to the respective stations in a predetermined time relationship, means for detecting the perforations in the said 35 records, comprising a source of light rays, which rays are adapted to pass through the perforations presented to the sensing station at differential times, and means for directing the light rays, 40 passing through the said records, at differential times, to impinge upon the different areas of the photographic record mediums presented to the recording station for recording the data upon the said record mediums.

9. A data reproducing machine comprising a 45 sensing station, means for feeding individual records successively past the sensing station, including a rotary transparent member, said records provided with differentially positioned perforations at different index point positions representing different data, a recording station, means for feeding photographic mediums successively past the recording station to present successively different index point positions thereto, means for operating the feeding means, in synchronism, so that the record elements are presented to the respective stations in a predetermined time relationship, means for detecting the perforations in the records and initiating individual beams of light rays, at differential times, whenever the perforations are detected, said detecting means, comprising a source of light rays disposed within the said rotary member, and means for directing the said beams of light, initiated at differential times, to impinge upon the photographic mediums at 55 the particular index point positions presented to the recording station for recording the data upon the said record mediums. 60
